US00D800334S

(12) **United States Design Patent** (10) **Patent No.:** **US D800,334 S**
(45) **Date of Patent:** **** Oct. 17, 2017**

(54) **CARRIER FOR CELL CULTURE**

(71) Applicant: **Pluristem Ltd.**, Haifa (IL)

(72) Inventors: **Harel Kasuto**, Kibbutz Yifat (IL);
Eytan Abraham, Frederick, MD (US)

(73) Assignee: **Pluristem Ltd.**, Haifa, IL (US)

(**) Term: **14 Years**

(21) Appl. No.: **29/499,986**

(22) Filed: **Aug. 20, 2014**

(30) **Foreign Application Priority Data**

Mar. 2, 2014 (IL) 55314

(51) **LOC (10) Cl.** **24-01**

(52) **U.S. Cl.**

USPC **D24/224**

(57) **CLAIM**

We claim the ornamental design for a carrier for cell culture, as shown and described.

DESCRIPTION

FIG. 1 is a perspective view of a carrier for cell culture according to our new design.

FIG. 2 is a front view thereof;

FIG. 3 is a rear view thereof;

FIG. 4 is a left side view thereof;

FIG. 5 is a right side view thereof;

FIG. 6 is top view thereof; and,

FIG. 7 is bottom view thereof.

1 Claim, 4 Drawing Sheets
